UNITED STATES PATENT OFFICE

LESLIE ERNEST BROUHAM, OF THORNTON HEATH, ENGLAND, ASSIGNOR TO THE ACCOUNTING & TABULATING CORPORATION OF GT. BRITAIN LIMITED, OF LONDON, ENGLAND

CARD PERFORATING MACHINE OR THE LIKE

Application filed January 10, 1930, Serial No. 419,976, and in Great Britain January 21, 1929.

This invention relates to card perforating machines or the like.

Card perforating machines are employed to make holes in cards at predetermined points thereby making the card a record card, and these holes are afterwards interpreted in what is known as a tabulating machine through which the cards are afterwards passed.

10 It is common practice to divide up the cards into zones involving sometimes six columns for each zone, and it is common practice also to allot zones for credit and debit accounts entered on the card by the perforating machine.

If the card is of an account in which the credit means an addition in the tabulator, then the zone in which the debit entries are made means that the tabulator has got to subtract.

20 Tabulating machines employ adding mechanism incorporating what is known as end to end transfer which permits the subtraction to be effected by addition of the complements of the numbers to be subtracted.

Now to effect the operation of the subtraction in the tabulator special cards have been used in the perforating machine, that is to say, cards which have an equal margin and in which the lines numbered 0 to 9 are 30 equally spaced from the edge.

By the use of such cards it is possible to invert the cards by a lateral movement to cause the hole in the 9 line to take place in the 0 line. In this way although a number is punched in a perforating machine its complement is actually operating the addition wheels in the tabulator.

One object of the present invention is to 40 eliminate the act of the operator of inverting the cards, thereby eliminating the chances of human error in this operation.

According to the present invention apparatus for producing record cards or the like for use in operating statistical machines comprises means for simultaneously making on a card direct and complementary records of an amount, said means also permitting a direct record only of the amount to be made.

50 Where the records are made by making per-

forations in the card, a punch perforating machine for this purpose is conveniently provided with means, whereby on the actuation of a single punch key, holes are punched simultaneously in the card in the lines corresponding to numbers complementary to one another. Thus if the key 2 is depressed for operating the punch, holes will be made both in the 2 and in the 7 line.

55 Preferably, complementary mechanism is incorporated so that as the carriage is traversing over the card normal setting may be effected in several zones and when a predetermined zone for example the credit zone is approached the complementary mechanism is introduced preferably automatically so as to produce a complementary setting in another zone for example the debit zone.

60 Alternatively, the complementary mechanism may be set by hand for use as and when required.

65 In the application of the invention to a punch for perforating machines as described in Arthur Thomas' co-pending application No. 419,974 now patent No. 1,858,174 filed on the 10th January, 1930 whether or not the carriage return mechanism is employed, the carriage may be constructed so as to punch either in the normal manner or so as to punch the complementary holes.

70 In order that the invention may be more clearly understood a carriage such as utilized in the machine described in co-pending application No. 419,974 now patent No. 1,858,174 filed on the 10th January, 1930, previously referred to will now be described with reference to the accompanying drawings in which:—

75 Fig. 1 illustrates the carriage in front elevation;

80 Fig. 2 illustrates the complementary plunger mechanism in perspective;

85 Fig. 3 illustrates a detail of the mechanism shown in Fig. 2;

90 Fig. 4 is a plan view of the carriage;

95 Fig. 5 is a cross sectional view through the machine illustrating the relative positions of the complementary mechanism, the punches and the carriage;

100 Fig. 6 illustrates in plan the stirrups con-

necting the complementary and normal plungers.

In the construction illustrated in the drawings the carriage 1 is provided with two sets of setting plungers, a set of normal plungers 2 and a set of complementary plungers 3. If there are ten set bars in a column there will be ten of each type of plunger disposed in a row across the field of set bars so as to be capable of being brought into register with any column of set bars. The normal plungers 2 are spaced apart from the complementary plungers 3 by a distance x which is equal to the distance between the commencements of the two zones in which the plungers are respectively intended to operate, the normal plungers being disposed in front of or nearer the left-hand end of the carriage, than the complementary plungers. 20 The carriage comprises a framework 1a which carries a bell crank lever 4 for each key of the machine, the bell crank being connected by Bowden mechanism 5 to its respective key 6 (Fig. 2). The depression of the 25 key causes the lever 4 to rock and the normal setting plunger 2 to be depressed, this plunger then depressing a set bar 7 which is in turn latched and afterwards co-operates with the corresponding punch 8 to effect a 30 recording operation.

In order that complementary punching may be carried out the bell crank 4 of the normal setting plunger 2 is connected by a link 9 to a stirrup 10 pivoted at 10a, so as to 35 constitute a rocking member, one arm of this stirrup being connected to a normal plunger while the other arm is connected to the corresponding complementary plunger. Thus if one arm of the stirrup is connected to a normal plunger which co-acts with the set bar corresponding to the numeral 3 the other arm will be connected to the complementary plunger which co-acts with the set bar corresponding to the numeral 6.

45 Conveniently, the link 9 is provided with a bayonet slot 9b which takes over a pin 2c on the toe 2a of the normal setting plunger 2 and the link 9 has beyond the closed end of its slot 9b a lug 9c to which the spring 2b assuring the proper setting of the normal 50 setting plunger 2 is attached.

The complementary plunger 3 is provided with a slot 3a into which is introduced a pin 11 on one arm of the stirrup 10, the other 55 arm being as before mentioned connected to the link 9 aforesaid.

The slot 3a in the complementary plunger 3 is reduced near its top conveniently by the provision of a knife edge or triangular projection 3b.

When the carriage is being used for ordinary perforating the complementary plunger 3 is disposed so that the pin 11 carried by the stirrup 10 rides in the slot 3a of the complementary plunger clear of the projection 3b

so that the operation of a key on the machine merely causes the bell crank 4 and normal setting plunger 2 to operate, the attached link 9 to be pulled down and the stirrup 10 rocked, but in view of the conditions above stated, the 70 rocking of the stirrup is an idle function.

If now, it is desired to make complementary perforations in a debit zone for a credit perforation, the complementary plungers 3 are rocked so as to bring the knife edge 3b under the pin 11 carried by the respective stirrup 10. Thereby, when the stirrup is rocked consequent upon the depression of a corresponding key the rocking motion is translated into a downward movement of the plunger 3 by reason of the pin 11 engaging over the knife edge 3b.

To control the position of the complementary plungers 3 automatically so that they are in the inoperative or the operative position, the complementary plungers are each carried for vertical displacement on a guide constituted by a rod 12, the complementary plunger being slotted at 3c for riding thereover.

The rod 12 on which the complementary plungers 3 are guided is itself carried in a frame 13 pivoted on the carriage.

This frame normally rests against stops on the carriage in which position the complementary plungers 3 are disposed so that the stirrups 10 rock idly.

Conveniently the complementary plungers are notched at 15 and the carriage 1 is provided with a bar 16 which lies in the notches 15 when they are set so that their stirrup 10 rocks idly. This definitely prevents the plungers 3 from dropping into operative position which might occur by a slight engagement of the pin 11 on the stirrup on the point or knife edge 3b of the complementary plunger 3.

The frame 13 is rocked automatically by the agency of a link 17 pivoted to the frame and to a second link 18 carrying a roller 19, the link carrying the roller being pivoted to the carriage at 18a.

The machine is provided with a cam path which constrains the movement of the roller 19 as the carriage traverses the field of set bars 7. Normally, this is a horizontal path so that the frame 13 on which the complementary plungers 3 are carried is not affected. To obtain automatically action from the complementary plungers 3 a guideway 20 slotted at 21 is provided on the side of the machine for the passage of the roller 19 (Fig. 3) and associated with this guideway is a manually operable member in the form of two parallel bar members 22, 23, connected by bridge pieces 24 which clear the operating roller 19 before referred to as it travels in the constraining slot 21 (see Fig. 3).

To the upper bar 22 is pivotally attached a latch member 25 provided with two notches 130

25a, 25b which provide two longitudinal positions for the bars by engagement over a fixed pin 26 on the machine frame. The bottom bar 23 of the pair is provided with cam slots 23a which ride over pins 27 fixed on the frame. In one of the positions of the latch 25 the pins 27 are at the bottoms of the slots 23a and in the other at the top.

In the position where the pins are at the bottom of the slot both bars are in the highest position and this causes an extended cam face 28 on the bottom bar 23 to overlap the constraining slot 21 for the roller 19, so that the roller is lifted up from its normal path thereby causing the operation of the frame 13 carrying the complementary plungers 3.

In such a construction it is convenient to make the normal slot 21 of wider form at the area where the extended cam face 28 of the lower bar overlaps and to form the upper bar 22 with a re-entrant portion 29 complementary to the extended cam face 28 on the bottom bar 23 as shown in Fig. 3, so that the roller 19 is positively guided throughout its path by riding in a slot from end to end wherein the normal path changes where the extended cam face 28 overlaps.

It will be understood that the length of the cam 28 cannot be longer than the distance "x" between the commencements of the two zones in which the normal and complementary plungers respectively operate; otherwise the complementary plungers 3 will release the set bars 7 set up by the plungers 2, as the carriage passes to the next zone. Further, it will also be clear that it is not possible to set up other information in the zone meant for complementary number punching.

By the present invention a perforating machine is operable to directly make the records necessary to cause a subtraction to be effected in the adding mechanism of a tabulator without any special manipulation of the cards. Moreover, the fact that the cards can be used the right side up when a subtraction is being made in the tabulator permits the use of other perforations in the card for special operations in the tabulator, which, of course, cannot be employed when the card is reversed unless such reversed card was perforated suitably so as to cause the simultaneous operation in the tabulator, a practice not employed because of the relative irregularities of the perforations so formed due to the fact that in the inverted position opposite edges of the card would be used for registering purposes.

Cards perforated by means of a machine constructed in accordance with the invention are subsequently passed through a tabulator which records the amounts punched on the cards, there being one card for each item in an account.

In a card perforating machine as described in co-pending application No. 419,

974 now Patent No. 1,858,174 filed on the 10th January, 1930, previously referred to there is a rock lever which is connected by a link to a lever pivoted on the carriage and carrying at its free end a roller which, when the rock lever is operated, presses in a juxtaposed release pawl and permits the release of a set bar by permitting the retraction of the locking bar.

Now in constructions according to the present invention where two sets of perforations are made at one and the same time, as for example in credit and debit columns, it is preferable to provide a device for clearing the actuated set bars in two different columns at one and the same time.

To this end a modified construction of a rock member, link and lever, is employed as illustrated in Fig. 1.

In this modified arrangement the arm on the lever is dispensed with and a similar arm 38 put on the other side of the pivot 39 so that the arm is depressed as a result of rocking the rock lever 40 in normal manner. To the arm 40 is pivotally connected an L bar 41 the lower part of the L being supported for lateral displacement. Conveniently, the bottom part 41a of the L is slotted at 41b to ride over a pin 42 carried by the carriage frame.

Symmetrically on each side of this pin support is a roller 43, the rollers being spaced so that they are operative on the release pawls 44 in the two zones where complementary perforations will be formed.

By such arrangement if the rock lever 40 is operated the arm causes a depression of the L member 41 and the consequential displacement of the rollers 43 on to the two release latches 44 desired to be operated.

It will be understood in such type of machine the path constraining the roller controlling the carriage of the complementary plungers is at the back of the machine, the release latches aforesaid, being on the front.

Although the invention has been described in relation to a punch in which the normal levers are operated by Bowden mechanism, other mechanical mediums may be employed as for instance compressed air or negative pressure in which case the plungers, instead of operating a Bowden cable may be in the form of pistons controlling the admission of the pressure or negative pressure as the case may be to the operative members.

Further, although the invention has been described by way of example in its application to a perforating machine as described in Arthur Thomas' co-pending application No. 419,974 now Patent No. 1,858,174 filed on the 10th January, 1930 it is not by limitation as the complementary mechanism may be employed on any card perforating machine, and further the invention may be used on a perforating machine for cards, sheets or

the like in which a back spacing mechanism and/or latch relieving mechanism is employed, as for example as described in the above co-pending application, and although the perforators have been referred to as machines in which cards are treated, this also is by way of example only as the invention comprises the application of the complementary punching device and the release mechanism to perforating machines which deal with paper in the strip form in which case the paper may be fed by mechanism as described in co-pending application No. 419,977 filed on the 10th January, 1930, in the names of 15 Arthur Thomas and Guy Sydenham English.

Although the present invention involving the use of complementary plungers has been described in its application to the production of complementary debit perforations when 20 credit perforations are being made this is by way of example only as complementary mechanism may be employed while punching debit perforations so as to produce complementary credit perforations.

25 In such an application of the invention the machine is preferably provided with two sets of keyboards, a normal set and a set of which the keys are connected to the complementary normal plungers of the carriage, for example the depression of the key 0 to the normal 30 board will in the usual way operate the normal 0 plunger and cause the operation of the complementary plunger 9. The same plungers will be operated by depressing the key 9 35 on the second keyboard.

Other means may be provided for effecting a duplex connection to the normal plungers to effect complementary punching in both directions, but as above stated it is preferred 40 to have a second keyboard.

What I claim is:

1. In a punch perforating machine for 45 making records on statistical record cards or strips the combination with the normal punching mechanism, of complementary punching mechanism, means for operatively connecting both of said mechanisms at a predetermined zone on a card or strip, means disconnecting the said mechanisms at other 50 zones on the said card or strip, and means for disabling the said first means at will.

2. In a punch perforating machine the combination of a carriage, a set of normal setting plungers carried by the carriage, a set of complementary plungers, a plurality of U-shaped connecting members, an arm of each connecting member connected to a normal plunger, a second arm of each connecting member, a connection between said arm and the corresponding complementary plunger and settable means to provide for selectively controlling said connection.

3. In a punch perforating machine the combination of a plurality of setting keys, complementary mechanism whereby holes are

punched in a card in the lines complementary to the numbers on said keys, means whereby as the carriage is traversing over the card normal setting may be effected in several zones, means whereby the movement of the carriage causes the complementary mechanism to be introduced and means for disabling at will the last mentioned means, whereby the carriage is ineffective to introduce the complementary mechanism. 70

4. In a punch perforating machine for making records on statistical record cards or strips the combination of a plurality of setting keys, a set of normal setting plungers, a set of complementary setting plungers, an operative connection between each key and a normal plunger, a normally inoperative connection between each normal plunger and its complementary plunger means for rendering operative the connection between each normal plunger and its complementary plunger at a predetermined zone on a card or strip, and means for disabling said means at will whereby normal setting may take place in all the zones of the card or strip. 80

5. In a punch perforating machine the combination of a carriage, means for moving said carriage, including a plurality of setting keys, a set of normal setting plungers, an operative connection between each key and a normal plunger, a set of complementary setting plungers, and means automatically actuated by the carriage during its traverse to connect each normal plunger to its complementary plunger and means for disabling said means at will, whereby the movement of the carriage is ineffective to connect the normal and complementary plungers. 90

6. In a punch perforating machine the combination of a carriage, means for moving said carriage, including a plurality of setting keys, a set of normal setting plungers, an operative connection between each key and a normal plunger, a set of complementary setting plungers, a normally inoperative connection between each normal plunger and its complementary plunger, and means whereby movement of the carriage automatically renders said connection operative when complementary punching is desired and means for disabling said means at will, whereby the movement of the carriage is ineffective to render the said connection operative. 100

7. In a punch perforating machine the combination of a carriage, a set of normal setting plungers carried by the carriage, a set of complementary setting plungers, a plurality of U-shaped connecting members, an arm on each connecting member connected to a normal plunger, a second arm on each connecting member and an operative connection between said arm and the corresponding complementary plunger. 110

8. In a punch perforating machine the combination of a carriage, means for moving

5 said carriage including a plurality of setting keys, a set of normal setting plungers, an operative connection between each key and a normal plunger, a set of complementary setting plungers, a plurality of U-shaped stirrup members, an arm on each stirrup member connected to a normal plunger, a second arm on each stirrup member, a normally inoperative connection between said arm and the 10 complementary plunger associated with said normal plunger and means whereby the movement of the carriage automatically renders said connection operative when desired.

9. In a punch perforating machine the 15 combination of a carriage, a set of normal setting plungers carried by the carriage, a set of complementary setting plungers, a plurality of U-shaped connecting members, an arm on each connecting member connected to 20 a normal plunger, a second arm on each connecting member, a pin carried on said second arm and adapted to ride in a slot formed in a complementary plunger, a transverse projection in said slot past which the pin can 25 normally slide without moving the complementary plunger, and means for displacing the complementary plunger until the projection is in the path of the pin whereby movement of the connecting member is then transmitted to the complementary plunger.

30 10. In a punch perforating machine the combination of a carriage, means for moving the carriage, a set of normal setting plungers carried by the carriage, a set of complementary setting plungers, a plurality of U-shaped connecting members, an arm on each connecting member connected to a normal plunger, a second arm on each connecting member, a pin carried on said second arm and adapted to ride in a slot formed in a complementary plunger, a transverse projection in said slot past which the pin can normally slide without moving the complementary plunger, and means whereby movement of the carriage effects displacement of the complementary plunger until the projection is in the path of the pin, whereby movement of the connecting member is then transmitted to the complementary plunger.

35 11. In a punch perforating machine the combination of a carriage, means for moving the carriage including a plurality of setting keys, a set of normal setting plungers an operative connection between each key and a normal plunger, a rocking frame, a set of complementary setting plungers mounted in said frame, means whereby the movement of the carriage automatically rocks the frame and means whereby the rocking of the frame 40 connects each normal plunger to its complementary plunger and means for disabling the first means at will, whereby the movement of the carriage is ineffective to rock the frame.

45 12. In a punch perforating machine the

combination of a carriage, means for moving the carriage, a set of normal setting plungers carried by the carriage, a rocking frame, a set of complementary setting plungers mounted in said frame, a plurality of U-shaped stirrup members, an arm on each stirrup member connected to a normal plunger, a second arm on each stirrup, a normally inoperative connection between said arm and the complementary plunger associated with said normal plunger, means whereby movement of the carriage causes rocking of the frame when desired, and means whereby such rocking of the frame renders operative the connection between the normal and complementary plungers.

50 13. In a punch perforating machine the combination of a carriage, means for moving the carriage including a plurality of setting keys, a set of normal setting plungers, an operative connection between each key and a normal plunger, a rocking frame, a set of complementary setting plungers mounted in said frame, a plurality of U-shaped stirrup members, an arm on each stirrup member connected to a normal plunger, a second arm on each stirrup member, a pin carried on said second arm and adapted to ride in a slot formed in a complementary plunger, a transverse projection in said slot past which the pin can normally slide without moving the complementary plunger, and means whereby movement of the carriage causes rocking of the frame when desired and means whereby such rocking of the frame renders operative the connection between the normal and complementary plunger.

55 14. In a punch perforating machine the combination of a carriage, means for moving the carriage including a plurality of setting keys, a set of normal setting plungers, an operative connection between each key and a normal plunger, a set of complementary setting plungers mounted in said frame, a plurality of U-shaped stirrup members, an arm on each stirrup member connected to a normal plunger, a second arm on each stirrup member, a pin carried on said second arm and adapted to ride in a slot formed in a complementary plunger, a transverse projection in said slot past which the pin can normally slide without moving the complementary plunger, and means whereby movement of the carriage causes rocking of the frame when desired and means whereby such rocking of the frame renders operative the connection between the normal and complementary plunger.

60 15. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

65 16. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

70 17. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

75 18. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

80 19. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

85 20. In a punch perforating machine the combination of a carriage, means for moving the carriage including a plurality of setting keys, a set of normal setting plungers, an operative connection between each key and a normal plunger, a set of complementary setting plungers, a member mounted on the carriage, a cam track normally disposed in the path of said member, means whereby movement of said member by said cam track at a predetermined point in the traverse of the carriage connects each normal plunger to its complementary plunger, means for removing the cam track out of the path of said member, and means for returning it into the path of said member.

adapted to ride in a slot formed in a complementary plunger, a transverse projection in said slot past which the pin can normally slide without moving the complementary plunger, a cam and a member carried by the frame and co-operating with said cam to rock said frame when the carriage reaches a predetermined point.

16. In a punch perforating machine the combination of a carriage, means for moving the carriage including a plurality of setting keys, a set of normal setting plungers, an operative connection between each key and a normal plunger, a rocking frame carried by the carriage, a set of complementary setting plungers mounted in said frame, a plurality of U-shaped stirrup members, an arm on each stirrup member connected to a normal plunger, a second arm on each stirrup member, a pin carried on said second arm and adapted to ride in a slot formed in a complementary plunger, a transverse projection in said slot past which the pin can normally slide without moving the complementary plunger, a cam, a member carried by the frame and co-operating with said cam to rock said frame when the carriage reaches a predetermined point, means for moving the cam into an operative position and means for moving said cam into an inoperative position.

17. In a punch perforating machine the combination of a carriage, means for moving the carriage, a set of normal setting plungers and a rocking frame carried on the carriage, a set of complementary setting plungers mounted in said frame, a plurality of U-shaped stirrup members, an arm on each stirrup member connected to a normal plunger, a second arm on each stirrup, a normally inoperative connection between said arm and the complementary plunger associated with said normal plunger, a relatively stationary member having formed therein a horizontal slot, a roller engaging with said slot, an operative connection between said roller and the frame, a cam member normally clear of the path of the roller in the slot, and means for moving said cam member into the path of the roller to rock said frame when the carriage reaches a predetermined point and thereby render said inoperative connection operative so that both direct and complementary setting take place.

18. In a punch perforating machine the combination of a carriage, means for moving the carriage including a plurality of setting keys, a set of normal setting plungers carried on the carriage, an operative connection between each key and a normal plunger, a rocking frame carried on the carriage, a set of complementary setting plungers mounted in said frame, a plurality of U-shaped stirrup members, an arm on each stirrup member connected to a normal plunger, a second arm on

each stirrup member, a pin carried on said second arm and adapted to ride in a slot formed in a complementary plunger, a transverse projection in said slot past which the pin can normally slide without moving the complementary plunger, a relatively stationary member having formed therein a horizontal slot, a roller engaging with said slot, an operative connection between said roller and the frame, a cam member normally clear of the path of the roller in the slot, and means for moving said cam member into the path of the roller to rock said frame when the carriage reaches a predetermined point and thereby bring the traverse projection into the path of the pin to operatively connect the complementary plunger with the normal plunger, so that both direct and complementary setting take place.

19. In a punch perforating machine the combination of a carriage, a plurality of columns of set bars, means for moving the carriage relatively to the set bars, a plurality of setting keys included in said means, a set of normal setting plungers, adapted to be associated by movement of the carriage with a column of set bars for setting the latter, an operative connection between each key and a normal plunger, a set of complementary setting plungers adapted to be associated by movement of the carriage with a different column of set bars for setting the latter, means whereby movement of the carriage automatically connects each normal plunger to its complementary plunger when desired, a rocking lever pivoted on the carriage, an L-shaped bar mounted to slide vertically on the carriage, an arm of said bar pivoted to the rocking lever, a plurality of latches each adapted to lock an actuated set bar in a column of set bars, and a plurality of projecting members carried on the L-shaped bar, each adapted to be associated with a latch during the traverse of the carriage, said projecting members engaging with and releasing the associated latches when the L-shaped bar is depressed.

20. In a punch perforating machine the combination of a carriage, a plurality of columns of set bars, means for moving the carriage relatively to the set bars, a plurality of setting keys included in said means, a set of normal setting plungers adapted to be associated by movement of the carriage with a column of set bars for setting the latter, an operative connection between each key and a normal plunger, a rocking frame carried on the carriage, a set of complementary setting plungers adapted to be associated by movement of the carriage with a different column of set bars for setting the latter, mounted in said frame, a plurality of U-shaped stirrup members, an arm on each stirrup member connected to a normal plunger, a second arm on each stirrup member, a pin

carried on said second arm and adapted to ride in a slot formed in a complementary plunger, a transverse projection in said slot past which the pin can normally slide without moving the complementary plunger, a relatively stationary member having formed therein a horizontal slot, a roller engaging with said slot, an operative connection between said roller and the frame, a cam member normally clear of the path of the roller in the slot, means for moving said cam member into the path of the roller to connect the normal and complementary plungers, a rock lever pivoted on the carriage, an L-shaped bar mounted to slide vertically on the carriage, an arm of said bar pivoted to the rock lever, a plurality of latches each adapted to lock an actuated set bar in a column of set bars, a column of set bars and a plurality of projecting members carried on the L-shaped bar each adapted to be associated with a latch during the traverse of the carriage, said projecting members engaging with and releasing the associated latches, when the L-bar is depressed.

In testimony whereof I affix my signature.
LESLIE ERNEST BROUGHAM.
